DESIGN FOR A CLAMP

James J. O'Neill, Oakland, Calif.

Application July 21, 1936, Serial No. 63,973

Term of patent 3½ years

To all whom it may concern:

Be it known that I, James J. O'Neill, a citizen of the United States, residing at Oakland, in the county of Alameda and State of California, have invented a new, original, and ornamental Design for Clamps, of which the following is a specification, reference being had to the accompanying drawing, forming part thereof.

Figure 1 is a top plan view of a clamp, showing my new design.

Figure 2 is a side elevational view.

Figure 3 is a front elevational view.

I claim:

The ornamental design for a clamp, as shown.

JAMES J. O'NEILL.
